WINDOW

Alfred B. Edwards, Jr., Plandome, N. Y.

Application April 2, 1946, Serial No. 659,079

16 Claims. (Cl. 160—90)

1.

This invention relates to windows, and is particularly applicable to combination or storm windows of the type having interchangeable glass and screen panels for year-round use.

It has been proposed heretofore to provide window assemblies comprising a frame for mounting the window in a building aperture, the frame being arranged to receive glazed and screened panels interchangeably, according to the season. The storage of the panel not in use, however, constitutes a considerable inconvenience, since twice a year, the panel in use must be removed, transported to a different part of the building, and the replacement panel brought back from storage for installation in the window. Provision of storage space for the panels not in use often presents a serious problem, particularly in apartment buildings where space is at a premium. The panels accumulate dust in storage and generally require cleaning before each installation.

Furthermore, it has been usual to provide panels which can only be installed or removed from the outside of the building, so that special equipment and the services of a skilled workman are required to change the panels twice each year.

For ventilation, glazed panels employed during the winter are usually arranged to swing outward from a building and to be fastened in this position during warmer periods for ventilation. This arrangement of the storm windows on a building presents an unsightly appearance, and also creates a serious hazard, in that sudden gusts of wind are likely to catch the panels and tear them from their supports.

It is an object of this invention to provide a window assembly of simple and durable construction, having a frame for mounting the window in a building aperture, wherein the screened and glazed panels can be interchangeably installed in a portion of the frame from the inside of the building.

A further object is to provide a window wherein the panel not in use can be conveniently stored in the frame itself so that the inconvenience of providing storage space for such panels, and transporting panels to and from storage is avoided.

Another object is to provide a window which can be opened inwardly for ventilating purposes instead of outward from the building.

These objects are accomplished in accordance with my invention by constructing a window with a frame adapted to receive upper and lower glazed panels in edge-abutting relation, supported against the inside of an abutment on the outer

side of the frame, the lower panel being pivotally mounted so as to swing inward about its upper edge when it is desired to open the window for ventilation. The frame is constructed so as to provide storage space for a third panel, interchangeable with the lower panel mounted for use so that the third panel can be mounted in the upper part of the frame inside of the upper panel.

Another feature of the invention is the provision of simple mounting means for removably securing the panels in the desired relation, and for storage in the frame; and the provision of simple latch means for holding the lower panel in open position for ventilation.

Other objects and advantages of the invention will appear from the following description of a preferred embodiment of my invention, taken with the accompanying drawings, wherein:

20 Figure 1 is a front elevation of a storm window in accordance with my invention, viewed from inside.

Fig. 2 is a broken side elevation of the storm window of Fig. 1, partly sectioned, and with parts cut away to show the underlying structure, and a screened panel stored therein.

Fig. 3 is an enlarged detail in an end elevation of the junction of the upper and lower panels, when mounted in the storm window.

Fig. 4 is an enlarged detail of means for securing the upper and lower panels in the frame.

Fig. 5 is a detail of a bolt or pintle for securing the lower panel in the frame.

Fig. 6 is a detail in front elevation of a latch member for holding the lower panel in open position.

Fig. 7 is a central vertical section of the latch member of Fig. 6.

Fig. 8 is a side elevation of the lower panel held in open position by the latch member of Fig. 6.

Fig. 9 is a detail of a keeper for holding the lower panel closed.

The present invention is illustrated as applied to a combination or storm window which comprises a frame 10, adapted to be mounted in a building aperture, e. g. on the outside of a permanent window installed therein, comprising a top transverse member 11, vertical side members 12, and a lower transverse member 13, secured together at the corners to provide a rigid structure. The top member 11 is provided with a flange 14, extending inward from the outside edge thereof, and the side members 12 are provided with an inwardly extending flange 15, in continuation of the flange 14, providing an abutment at

the outer edge of the frame for supporting panels to be installed therein. The lower transverse member 13, is constructed to have a raised ledge 16, adjacent the outside of the frame for engaging the lower edge of a panel installed in the window, and a lower ledge 17 on the inside of the frame. The upper portions of the side members 12 are also provided with an inwardly extending flange 18 at the inner edge of the frame forming an inner abutment, extending downward partway from the top of the frame, terminating at 18a preferably above the middle of the frame so as to permit insertion of panels from the inner side of the frame.

An upper glazed panel 19, comprising a frame 20 and a glass pane 21 mounted therein, is constructed to fit the upper half of the frame 10. Means for mounting the upper panel in the frame comprises a throw-bolt 22, secured to the inner surface of the lower rail of frame 20, for example, by means of screws 23 engaging a pair of slots 24 in the bolt 22, so that the end of the bolt can be projected beyond or retracted within the side edges of the frame 20. A corresponding aperture 25 is provided in a side member 12 to receive the end of the throw-bolt 22 when the panel 19 is positioned in the upper part of the frame 10 against flanges 14 and 15 on the outside of the frame. The upper portion of the panel 19 is held against flanges 14 and 15 by a pair of springs 26 mounted on the inner surfaces of side members 12 of the frame, for example, by means of a yoke 26'.

The upper panel 19 is installed in the frame by sliding it upward between flanges 15 and springs 26 with bolt 22 in retracted position, and after the panel is properly positioned, projecting the bolt 22 into the aperture 25. If desired the bolt can be secured in projected position by tightening screws 23.

A lower panel 27 for winter use, comprising a frame 28 and a glass pane 29 mounted therein, is constructed for mounting in the frame 10 against the flanges 15 with its upper edge in abutting relation with the lower edge of upper panel 19, and its lower edge contacting the raised ledge 16 of the lower transverse member 13 of the frame 10. Means are provided for removably mounting the lower panel in the frame in such a manner that it is adapted to pivot about a horizontal axis adjacent its upper edge, swinging inward from the frame for ventilation. Such mounting means comprises, for example, a pair of pintles 30 at each end of the top of the panel frame 28, each having a laterally projecting thumb piece 31 intermediate the ends thereof, and a spring-centering shoulder 32 at the inner end thereof. The pintles 30 are slidably housed in sockets 33 in the upper rail of the panel frame 28 with thumb pieces 31 projecting through slots 34 in the inner surface of the frame 28, so as to limit movement of the pintles between projected and retracted positions at the sides of the panel. The edges of the slots 34 are preferably provided with a pair of notches 35 and 35a at opposite ends of the slots, for receiving the thumb pieces 31, so as to latch the pintles 30 in projected or retracted position. A compression spring 36 in the interior of the socket 33 bears against the shoulder 32 urging the pintle toward projected position. A pair of apertures 37 are provided in the side 12 of the frame 10 for receiving the projecting pintles 30, when the lower panel 27 is mounted in the frame against flanges 15, abutting the lower edge of upper panel 19, and rest-

ing on ledge 16 of the lower transverse member 13 of the frame.

In order to permit inward pivoting movement of panel 27 about the axis of pintles 30, while at the same time permitting the panel to remain in surface contact at its upper edge with the lower edge of upper panel 19, the contacting surfaces of the two panels are formed with complementary cylindrical portions 38, concentric with pintles 30, preferably terminating in a plane portion 39 on the outside of the panels when both are positioned against the flanges 15. At the cylindrical contact surface portions 38, the lower panel is preferably convex while the upper panel is concave.

The lower panel 27 is installed in the frame with pintles 30 latched in retracted position, as by engaging the thumb pieces 31 with the inner notches 35 of slots 34, and the panel is inserted in the frame from the inside, with its cylindrical upper edge surface abutting the corresponding surface on the lower edge of the upper panel. When its lower edge rests upon the ledge 16 of the lower member 13 of the frame, the pintles 30 are released for projection into the apertures 37 in the frame by moving the thumb pieces 31 out of the inner notches 35, whereupon the springs 36 project the pintles into the apertures and the pintles 30 can be locked in projected position by moving the thumb pieces 31 downward into the outer notches 35a.

It will be seen that the panel 27 can swing inward from the frame about the pintles 30, while maintaining surface contact at the cylindrical surface 38 with the upper panel 19. In order to hold the panel 27 closed, a pair of keepers 40 are pivotally secured at 41 to the vertical inner side 42 of ledge 16, and can be moved upward about their pivots so that they project across the inner surface of the frame 28 to hold panel 27 against flanges 15.

In accordance with the invention, means for latching the lower panel 27 in various open positions for ventilation comprises a latch member 43, formed for example of metal rod, having a handle 44, and a pair of parallel arms 45 and 46, the ends of which are bent inwardly at right angles to form an inner cross bar 47 and an outer cross bar 48, spaced one from the other, so as to enclose an area open at one side of the latch member. The latch member 43 is fastened to the inside of the bottom rail of the frame 28 of the lower panel 27 by means of a yoke 49, which can be stamped from a piece of sheet metal, including a pair of vertical guides 50 for engaging arms 45 and 46, and a raised portion 51 for receiving the cross bars 47 and 48 within the limits of the frame 28 upon moving the latch member 43 upward thereon. Upward movement 60 of the latch member 43 in the guides 50 is limited by an inward projection 52 between the guides.

When it is desired to use the latch member, the parallel arms 45 and 46 slide downward through the guides 50 so that the cross bars 47 and 48 are below the edge of the window, the handle 44 limiting downward movement of the latch member upon reaching the top of yoke 49.

A latch bar 53, having on its upper surface a series of notches 54 is constructed of a thickness corresponding to the spacing between the cross bars 47 and 48 of the latch member 43. The latch bar is mounted on the lower member 13 of the frame 10 for pivotal movement about one end thereof by means of a pin 55 projecting lat-

erally from one end of the bar through a hole 56 in the inner ledge 17 at the bottom member 13 of the frame, the hole and pin having sufficient clearance to permit the latch bar 53 to be canted upward as well as moved pivotally in a horizontal plane. A retaining member such as a washer 51 is secured to the lower end of the pin and a compression spring 58 mounted on the pin bears against the washer and the under surface of the ledge 17 on the frame 10, normally retracting the inner end of the latch bar 53 toward the surface of the ledge 17. When not in use the latch bar is moved about its pivotal mounting until it rests on the ledge 17, and is held in this position against casual displacement by the force of the spring 57.

When it is desired to latch the lower panel 27 in open position for ventilation as shown in Fig. 8, the panel is opened, pivoting inward about the pintles 30. The latch member 43 is projected downward from the lower edge of the panel and the latch bar 53 is moved into position between the cross bars 47 and 48 of the latch member arm 43 and engaged with one of the notches 54 said cross bars yielding resiliently to permit the insertion of the latch bar between them. The latch means thus provides a convenient and simple arrangement for holding the lower panel in open position for purposes of ventilation.

A screen panel 59 having a frame 60 covered with screening 61 is constructed so as to be interchangeable with the lower glazed panel 27. Thus, it includes a convex cylindrical portion 38a at its upper edge for mounting in an abutting relation with the corresponding concave cylindrical surface 38 on the lower edge of the upper panel 19. Since this screen does not pivot in position, it includes only a single pintle 30a, with a thumb piece 31a mounted in the upper rail of its frame, in the same manner as the pintles 30 in the panel 27 to serve as a latch. Thus, the screened panel can be interchangeably mounted in the lower portion of frame 10 replacing the glazed panel 27.

In accordance with the invention, the frame 10 is constructed of sufficient depth to receive the screen panel 59 (or glazed panel 27) in the upper portion of the frame, facing the inside of upper panel 19 so that either of the interchangeable panels can be stored in the upper part of the frame, facing the inside of upper panel 19, while the other of the interchangeable panels is installed for use in the frame. For this purpose, one or a pair of holes 62 are provided in the side members 12 of the frame 10 for receiving pintle 30a (or 30) when one of the lower panels is placed in the upper portion of the frame in inverted position, resting against the inner flanges 18 of the side members 12, and extending upward toward the top of the frame. A spring 26a advantageously carried by yoke 26 is provided at the sides of the frame to hold the stored panels against the flanges 18.

In order to mount one of the panels, for example, the screen panel 59 in position for storage after removal from the frame, the panel is inverted, its lower edge being inserted between the upper panel 19 and the inner flanges 18 on the side members 12 of the frame. It is then slid upward between said flanges and springs 26a until the pintle 30a registers with the corresponding hole 62 in the sides of the frame 10. The pintle is then projected and the screen panel is conveniently stored for the winter season.

It will be seen that the window of my inven-

tion provides a convenient and simple arrangement, with the provision for storing interchangeable screen and glazed panels when not in use in the upper portion of the window. Since the space between the upper panel and the permanent window in the building aperture in which the panel used is stored is protected from substantial circulation of air, there is little tendency for dust to accumulate on the stored panel, so that it ordinarily requires very infrequent cleaning. When it is desired to wash the glazed panels, their inner surface can be readily reached by removing the stored panel, and lowering the upper sash of the permanent window; and when it is desired to wash the entire window, including the outer surface thereof, the upper and lower panels are removed so that the panels may be brought into the building and readily cleaned. The surface abutment provided at cylindrical surfaces 38 of the upper and lower glazed panels provides a weather-tight seal, while at the same time permitting pivotal mounting of the lower panel in the frame.

Variations and modifications may be made within the scope of this invention and portions of the improvements may be used without others.

I claim:

1. An auxiliary window unit comprising a frame adapted to be mounted in a window opening for receiving an upper and lower panel, latch means removably mounting an upper panel in said frame, latch means removably mounting a lower panel in said frame, and latch means removably mounting a third panel of similar outline to said lower panel interchangeable with said lower panel in the upper part of the frame facing the upper panel mounted in the frame.

2. An auxiliary window unit comprising a frame adapted to be mounted in a window opening for receiving an upper and lower panel, latch means removably mounting an upper panel in the outer portion of said frame, latch means removably mounting a lower panel in said frame, and latch means removably mounting a third panel of similar outline to said lower panel interchangeable with said lower panel in the upper portion of the frame facing the inside of the upper panel mounted in the frame.

3. An auxiliary window unit comprising a frame adapted to be mounted in a window opening for receiving an upper and lower panel, latch means removably mounting an upper panel in the outer portion of said frame, latch means removably mounting a lower panel in said frame in edge abutting relation with said upper panel, and latch means removably mounting a third panel of similar outline to said lower panel interchangeable with said lower panel in the upper portion of the frame in inverted position, facing the inside of the upper panel.

4. An auxiliary window unit comprising a frame adapted to be mounted in a window opening, an upper panel mounted in the upper portion of said frame, a lower panel and a third panel interchangeable therewith for mounting in the lower portion of said frame, mounting means on said lower panel and on said third panel, and cooperating means on said frame for removably mounting these panels interchangeably in the lower portion of the frame, and means on the frame for cooperation with the mounting means on said lower panel and third panel for mounting these panels interchangeably in the upper portion of the frame in inverted position facing the inside of the upper panel.

5. An auxiliary window unit comprising a frame adapted to be mounted in a window opening, an upper panel for mounting in the upper part of said frame, a lower panel for mounting in the lower portion of said frame, a third panel interchangeable with said lower panel, pivot mounting means at the top of said lower panel and of said third panel and cooperating means on said frame for mounting these panels interchangeably in the frame, for pivotal movement about the top of the panels, and means on the frame for cooperation with said mounting means on the lower panel and third panel for mounting these panels interchangeably in the upper portion of the frame, in inverted position facing the inside of the upper panel.

6. An auxiliary window unit comprising a panel-receiving frame adapted to be mounted in a window opening, an abutment at the outer edge of said frame, latch means securing an upper panel against the inside of said abutment in said frame, latch means removably securing a lower panel against said abutment in edge-abutting relation with the upper panel, and latch means releasably securing a third panel of similar outline to said lower panel in the upper portion of said frame facing the inside of said upper panel, said third panel being interchangeable with said lower panel.

7. An auxiliary window unit comprising a panel-receiving frame adapted to be mounted in a window opening, an outer abutment at the outer edge of said frame, an inner abutment at the inside edge of the upper portion of said frame, means for securing an upper panel against the inside of the outer abutment, pivot means for removably releasably securing a lower panel against said outer abutment in edge-abutting relation with said upper panel and facilitating inward pivotal movement of the lower panel about the upper edge thereof, and means for releasably securing a third panel against said inner abutment in the upper portion of said frame facing the inside of said upper panel, said third panel being interchangeable with said lower panel.

8. An auxiliary window unit comprising a panel-receiving frame adapted to be mounted in a window opening, an outer abutment at the outside edge of said frame, an inner abutment at the inside edge of the upper portion of said frame, an upper panel mounted in the upper portion of said frame against the inside of said outer abutment, means for securing the lower end of said panel to said frame, resilient means carried by said frame for urging the upper part of said upper panel against said outer abutment, a lower panel mounted in said frame against said outer abutment in edge-abutting relation with said upper panel, releasable pivot means on said lower panel and cooperating means on the frame for securing the upper end of the lower panel to the frame and to facilitate inward swinging of said lower panel about its upper end away from said outer abutment, a third panel interchangeable with said lower panel and having means for holding the latter in inverted position in the upper portion of the frame against said inner abutment, and resilient means mounted on frame for urging said third panel against said inner abutment.

9. In a storm window, a panel-receiving frame, an upper panel secured in the upper portion of said frame, a lower panel for mounting in the lower portion of said frame in edge-abutting relation with said upper panel, the contiguous edges

of said panels having complementary cylindrical surface portions providing surface contact between the panels, and pivot means for securing said lower panel in the frame, said pivot means being concentric with said cylindrical surface portions facilitating inward pivotal movement of the lower panel about its upper end while maintaining surface contact with said upper panel at said cylindrical surfaces.

10. In a storm window, a panel-receiving frame, an outer abutment at the outside edge of said frame, an upper panel removably secured in the upper portion of the frame against the inside of said abutment, a lower panel for mounting in the lower portion of said frame in edge-abutting relation with said upper panel, the contiguous edges of said panels having complementary cylindrical surface portions in surface contact, concave on the upper panel and convex on the lower panel, and plane surface portions on the outer edges of said panels in surface contact when said lower panel lies against said abutment, pivot means on said lower panel concentric with said cylindrical surfaces, and cooperating means on the frame for mounting said lower panel therein for inward pivotal movement about its upper end while maintaining surface contact with said upper panel at said cylindrical surfaces.

11. In a storm window, a panel-receiving frame, an outer abutment at the outside edge of said frame, an upper panel removably secured in the upper portion of the frame against the inside of said abutment, a lower panel for mounting in the lower portion of said frame in edge-abutting relation with said upper panel, the contiguous edges of said panel having complementary cylindrical surface portions in surface contact, concave on the upper panel and convex on the lower panel, a pair of pintles mounted in the top rail of said lower panel concentric with said cylindrical surface and movable between retracted and projected positions, latch means for holding said pintles in said retracted and projected positions, and apertures in said frame for receiving said pintles when projected for holding said lower panel in the frame, said pintles supporting the panel for pivotal movement about its upper end while maintaining surface contact with said upper panel at said cylindrical surfaces.

12. In a storm window, a panel-receiving frame, an upper panel mounted in the frame; a lower panel mounted in the frame in edge-abutting relation with said upper panel; a raised ledge at the base of the frame for engaging the lower edge of said lower panel, the lower panel being swingable about its upper end, inwardly from said frame; a latch bar mounted on the base of the frame inwardly from, and below the level of said ledge, said latch bar being horizontally, pivotally mounted and tiltably movable about one end thereof, and lying flat against the inside of said ledge in one position and being movable to a position projecting inward and upward from said ledge; and latch means mounted on the lower panel for cooperation with said latch bar when the latter is moved to projected position, for holding the lower panel in inwardly tilted position about its pivotal mounting.

13. In a storm window, a panel-receiving frame, an upper panel mounted in the frame; a lower panel mounted in the frame in edge-abutting relation with said upper panel; a raised ledge at the base of the frame for engaging the lower edge of said lower panel, the latter panel being mounted for pivotal movement about its upper

end, inwardly from the frame; an apertured horizontal ledge on the frame below the level of the first named ledge, and located inwardly thereof; a latch bar having a pin projecting at right angles thereto at one end thereof, said pin being loosely held in the aperture in the lower ledge of said frame and providing horizontal pivotal movement as well as tilting movement of said latch bar about the pin at one end thereof; and latch means mounted at the lower end of said lower panel for engaging said latch bar when the latter is moved to a projected position for holding the panel in inwardly tilted position about its pivotal mounting.

14. In a storm window, a panel-receiving frame, an upper panel mounted in the frame, a lower panel mounted in the frame in edge-abutting relation with said upper panel; a raised ledge at the base of the frame for engaging the lower edge of said lower panel, the lower panel being pivotally swingable about its upper end, inwardly from the frame; a latch bar mounted on the base of the frame inwardly from and below the level of said ledge, said latch bar being swingable in a horizontal plane as well as tilttable about one end thereof, said bar lying flat against the inside of said ledge in one position and being movable to a position projecting inward and upward from said ledge; and a latch member on the lower panel comprising a pair of resilient vertically spaced horizontal clamp members open at one side for receiving and clamping said latch bar between them when the bar is moved to projecting position, said latch member being movable on said panel between a downwardly projecting position to engage said latch bar, and an upwardly retracted position when disengaged therefrom.

15. In a storm window a panel-receiving frame, an upper panel mounted in said frame, a

10

lower panel pivotally mounted at its upper edge in the frame for inward pivotal movement, said panel having an upper surface in edge-abutting relation with said upper panel in all pivoted positions, and releasable latch means at the lower part of said lower panel and on the lower part of said frame for holding the lower panel in inwardly pivoted position, said latch means including a latch bar having a plurality of notches for supporting the lower panel in various angles of inclination.

16. In a storm window, a panel-receiving frame, an upper panel mounted in the frame; a lower panel mounted in the frame in edge-abutting relation with said upper panel; the lower panel being swingable about its upper end, inwardly from said frame; a latch bar mounted on the base of the frame, said latch bar being horizontally swingable as well as tilttable about one end thereof, and lying flat in one position and being movable to a position projecting inward and upward; and latch means mounted on the lower panel for cooperation with said latch bar when the latter is moved to projected position, for holding the lower panel in inwardly tilted position about its pivotal mounting.
